United States Patent Office

Des. 188,119
Patented June 7, 1960

188,119

AMUSEMENT GAME CABINET

Jerry C. Koci, Barrington, Ill., assignor to Chicago Dynamic Industries, Inc., Chicago, Ill., a corporation of Illinois

Filed Feb. 17, 1959, Ser. No. 54,642

Term of patent 3½ years

(Cl. D34—5)

Fig. 3.

Fig. 1 is a perspective view of the amusement game cabinet showing my new design;

Fig. 2 is a side elevational view, the opposite side being substantially the same and the back being substantially plain; and

Fig. 3 is a top plan view thereof.

I claim:

The ornamental design for an amusement game cabinet, as shown and described.
